DESIGN FOR A DISPLAY STAND

Allen A. Wright, Winnetka, Ill., assignor to Kraft-Phenix Cheese Corporation, Chicago, Ill., a corporation of Delaware

Application March 4, 1935, Serial No. 55,699

Term of patent 14 years

To all whom it may concern:

Be it known that I, Allen A. Wright, a citizen of the United States, residing at Winnetka, in the county of Cook and State of Illinois, have invented a new, original, and ornamental Design for a Display Stand, of which the following is a specification, reference being had to the accompanying drawing, forming part thereof.

The figure is a perspective view of a display stand, showing my new design.

I claim:

The ornamental design for a display stand, substantially as shown.

ALLEN A. WRIGHT.
